(57) **CLAIM**

The ornamental design for a cover for mobile phone, as shown and described.

DESCRIPTION

FIG. 1 is a front perspective view of a cover for mobile phone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The dot-dash broken line shown in FIGS. 1 and 2 represents a boundary of the claimed design. The dash-dash broken lines throughout the drawing figures depict unclaimed environment. The broken lines form no part of the claimed design.

1 Claim, 7 Drawing Sheets

FIG. 1
